SELF-BALANCED QUILTING MACHINE

Walter H. May, Pelham Manor, N. Y., assignor
to Carlin Comforts, Inc., New York, N. Y., a
corporation of New York

Application April 16, 1930. Serial No. 444,712

5 Claims. (Cl. 112—117)

This invention relates to a machine for sewing irregular and perhaps intricate and fancy designs in a fabric.

It is especially adapted for sewing quilts or 5 comforters which are usually made up of two layers of woven fabric such as silk, imitation silk, or cotton with a filler in between.

It is an object of this invention to produce a machine upon which a full size quilt may be placed 10 and the surface of the quilt brought into co-operative relationship with the operating head of a sewing machine to cause the stitching to follow any predetermined design.

It is also an object to produce such a machine 15 which is readily adjustable to accommodate quilts of various sizes and it is a further and final object to produce these desirable results with a mechanism which is reliable, economical to operate and manufacture and compact in structure 20 despite the fact that it is capable of handling standard sized quilts.

Further features and objects of this invention 25 will be more fully understood from the following detailed description of the accompanying drawings, in which

Fig. 1 is a side elevation of a machine embodying my invention.

Fig. 2 is a plan view of the same machine illustrated in Fig. 1.

30 Fig. 3 is a sectional elevation taken through 3—3 of Fig. 2.

Fig. 4 is a section taken through 4—4 of Fig. 1.

Fig. 5 is a section taken through 5—5 of Fig. 3.

Fig. 6 is a section taken through 6—6 of Fig. 4.

35 Fig. 7 is a section taken through 7—7 of Fig. 4, and

Fig. 8 is a section taken through 8—8 of Fig. 4.

Viewing the drawings and especially Figs. 1, 2 and 4, the frame is illustrated as made up of 40 end members 1 and 2 comprising horizontal pieces 3 and 4 and vertical pieces 5, 6, 7, 8 and 9.

As here illustrated, these end members are cast in one piece, preferably of a malleable iron or steel casting. The base portion of the end members 45 are connected together by tie rods 10 and 11 and the upper ends of the end members are connected together by a channel member 13. Intermediate the tie rods and the channel member is a supporting channel 15 and a track member of 50 T-shaped cross section illustrated at 17. An auxiliary supporting plate is illustrated at 20 and serves to support the rear or drive end of the sewing machine which will be described in detail hereafter. A supporting plate 21 disposed immediately below the supporting plate for the sew-

ing machine is adapted to support an electric motor 22 and these plates are joined together by a strut 23 and also joined at the left ends thereof as viewed in Fig. 1 to the framework thus providing a strong and rigid support for the sewing 60 machine and a motor drive therefor.

The sewing machine equipment is similar to the standard sewing machine, except however that the sewing head is spaced from the drive or fly wheel end of the machine and, of course, in like 65 manner space the the spindle operating mechanism and dog feed from the drive or fly wheel end of the machine.

Inasmuch as the sewing machine per se is of 70 standard construction except for the spacing of the elements thereof, it is not believed that it is necessary to describe it in detail and so only a brief description will be given.

The rear fly wheel or driving portion of the 75 machine is shown at 30 with the usual fly wheel 31 and pulley 32 attached and adapted to be connected to electric motor 22 by means of a belt 33. A shaft 35 connects the drive end of the sewing machine to the sewing head illustrated at 36 and it has been found advisable to equip 80 this shaft with an intermediate bearing shown at 37 in order to do away with vibration and "whip".

It should be noted at this point that the sewing 85 head 36 is positioned at substantially the mid-point of the main framework for reasons which will be made clear hereinafter.

The spindle operating mechanism and the dog feed which co-operates with the pressure foot is driven from the driving head 30 through shafts 90 39 and 40 illustrated in Fig. 3.

A supporting plate immediately below the presser foot is illustrated at 41 and has an articulate shape in order that it may conform to the shape of the quilt as disposed upon the ring 95 frame.

The motor 22 is of the standard variable speed type which is commonly used for driving sewing machines and is controlled by a foot treadle 42 (Fig. 4) pivotally secured at 43 to rock shaft 44 100 which is adapted to oscillate with the treadle and which in turn is connected by a suitable linkage, as shown at 45 and 46 to a variable speed control mechanism 50, with the result that an operator standing before the machine may, by 105 the proper manipulation of treadle 42 control the speed of the sewing machine mounted on the top of the frame.

110 A revolvable framework upon which the quilt or comforter to be sewed is mounted is adapted

to slide longitudinally of the framework and at the same time rotate about an axis substantially through the center of T-rail 17. This framework consists of rings 52 and 53, which are mounted to freely rotate upon sleeve 54 which in turn is adapted to slide longitudinally of the framework along T-rail 17. The sleeve 54 is supported by a pair of yokes 55 and 56 which carry axles 57 and 58 respectively, upon which pulleys 59 and 60 are freely rotatable. These pulleys in turn engage one edge of the T-rail 17 at slots 61 and 62 cut through the sleeve 54.

As illustrated in Fig. 5, the pulleys are shown with V-shaped notched faces 66 adapted to engage the upper edge of the vertically disposed web of the T-rail 17. The T-rail 17 is beveled to form an angle complementary to and adapted to fit within the V-shaped notch 66. An auxiliary T-rail 67 is disposed above and in parallel relation to the main supporting T-rail 17 and is furnished for the purpose of producing additional stability for the quilt carrying frame. This T-rail is supported from main channel 15 by suitable brackets illustrated at 67. Pulleys 63 mounted upon suitable supporting arms 69 attached to tubular member 54 engage and co-operate with the T-rail 67 to prevent an upward movement of the main frame. The rings 52 and 53 are adapted to be joined together by a telescoping member illustrated in detail in Fig. 7 and shown in section in Fig. 4 which I have numbered 70. Each ring is equipped with an arm 71 (Fig. 4) and one member, such as the internal member 70a of the telescoping connecting link 70 is connected to one arm and the other member, that is the external member 70b, is connected to the other arm. Set screw 72 is adapted to lock the complementary members of the telescoping adjusting rod together. At 75 in Fig. 4 is illustrated a counterweight to balance the weight of arm 71 and the parts connected thereto so that the rings will be in perfect balance and will not tend to rotate no matter what position they are left in.

An additional support for the T-member 17 is furnished immediately below the sewing machine head for the purpose of maintaining a constant distance between the sewing mechanism and the T-shaped rail 17. This additional support is shown in detail in Fig. 5 and comprises a U-shaped member 80 connected at the upper ends thereof to channel 15 and adapted to hang therefrom and having an adjusting screw 81 at the lower end thereof with a locking nut 82 and so disposed relative to sleeve 54 and T-rail 17 as to pass upwardly through a slot 83 (Fig. 3) in the sleeve 54 and engage the lower side of T-rail 17 to support the same and prevent undue sag therein because of the weight of the framework and comforter which is supported by the rail 17.

A mechanism is provided to co-operate with the ringed framework and is adapted to enable an operator to rotate the framework and at the same time to move it longitudinally back and forth along the T-rail. This mechanism is illustrated in Figs. 1, 2, 3, 4 and 8, and comprises two arms 90, 91, pivoted at the centers thereof upon sleeve 54 as shown at 92 and 93 respectively, and adapted to freely rotate on sleeve 54. The upper ends of these arms are connected together by an adjustable telescoping member 94 comprising an inner and an outer tube, illustrated at 94a and 94b respectively and adapted to be locked together by lock nut 95. Attached to and depending from member 94 in parallel relationship

thereto is a rod-like handle 97 mounted on bolts 98 and 99 and spaced from the member 94 by springs 100, 101 and 102. The length of this member is adjustable by means of the slot and pin connection shown at 105 so that it will slide to increase and decrease its length as the adjustable telescoping member 94 is adjusted. This rod 97 is so disposed relative to the member 94 that when the operator's hands rest upon the member 94, the rod 97 may be grasped by the fingers and squeezed upwardly toward the member 94. Near each end of the rod 97 is disposed a pin 107 and 108 adapted to engage a series of holes drilled through the periphery of each of the rings 52 and 53, as shown in Figs. 1, 2 and 3, for instance, at 109. When rod 97 is squeezed upwardly toward telescoping member 54, pins 107 and 108 will become disengaged from the holes in the periphery of the rings and when released the member 97 will be forced downwardly by the springs 100, 101 and 102, so that the pins will be forced into engagement with the holes on the rings. The opposite ends of arms 90 and 91 are connected by a telescoping member 110 which is equipped with counterweights 111 and 112 furnished to balance the indexing mechanism so that it may be readily operated with a minimum of physical effort.

The sleeve 54 is equipped with a pair of adjustable collars 115, 116 (Fig. 3) adapted to maintain the indexing members and the rings in their proper relative position. These collars are equipped with set screws 117 and 118 so that they may be securely locked to the sleeve 54.

The periphery of each of the rings is equipped with a series of clamps, one of which is illustrated in detail in Fig. 6 and which comprises a clamping finger 120 urged downwardly into clamping contact with the periphery of the ring by means of a spring 121. The clamping portions 115 of these fingers are equipped with emery cloth or sand paper illustrated at 122 and in like manner the periphery of the ring which is adapted to co-operate with the clamping fingers is equipped with emery cloth as shown at 123.

Each ring is equipped with a series of these clamps around the periphery thereof and the clamps are so positioned relative to the indexing holes that they do not interfere with the proper co-operation of the indexing pins 107 and 108 with the indexing holes.

In operation a comforter C upon which it is desired to sew a fancy design is secured to the periphery of the rings by means of the spring operated clamping fingers 120. This may be accomplished by first adjusting the spacing of the rings relative to each other and then subsequently securing the comforter to the periphery thereof where it may be securely attached with the aid of the emery cloth and clamping fingers and preferably put under a slight tension in order to keep it stretched. When the comforter to be worked upon is so positioned, the operator may rotate the ring-like frame about the T-rail as a center with the aid of the mechanism provided to cooperate with the ring framework and at the same time slide the rings longitudinally of the framework of the machine along the track 17 until the desired point is brought under the sewing machine, then the sewing machine is started and the operator may follow out any predetermined design of sewing upon the comforter by merely moving the framework back and forth upon the track 17 and rotating it with the aid of the sewing-line indicating mechanism about

the sleeve 54. In this manner, a complete universal movement is accomplished and an entire comforter which is a large and unwieldy article is quite readily moved around under the sewing machine head in order that any predetermined path of stitching may be followed.

Whereas I have described the invention by reference to specific forms thereof, it will be understood that many changes and modifications may be made without departing from the spirit of the invention.

I claim:—

1. In a machine of the character described, a sewing machine, a hollow open frame for supporting an article to be sewed, said open frame comprising circular members adjustably spaced apart from each other, a fixed single trackway disposed substantially axially of said circular members, a tubular member enclosing said single trackway, means carried thereby engaging the trackway to permit axial movement of the tubular member, and said open frame rotatably mounted on said tubular member.

2. In a machine of the character described, a sewing machine, an open frame for supporting an article to be sewed, said open frame comprising circular members adjustably spaced apart from each other, bearings in the axes of said circular members, a trackway extending through said bearings, and means for rotatably supporting said open frame on said trackway, whereby said frame may be at will rotated and/or displaced in an axial direction.

3. In a machine of the character described, a sewing machine, an open frame for supporting an article to be sewed, said open frame comprising circular members provided with radial-

ly extending elements, bearings secured to the said elements in the axis of the circular members, means for spacing the circular members apart from and parallel to each other, a stationary trackway extending through said bearings, and means for rotatively supporting said open frame on said trackway, whereby said frame may be at will rotated and/or displaced in an axial direction.

4. In a machine of the character described, a sewing machine, an open frame for supporting an article to be sewed, said open frame comprising circular members spaced apart from each other, a trackway extending through the axis of said open frame, a tubular shaft mounted for axial movement on said trackway, said open frame rotatably mounted on said shaft, and frame position regulating means secured to said open frame and extending radially from the frame beyond the supported article.

5. In a machine of the character described, a sewing machine, an open frame for supporting an article to be sewed, said open frame comprising spaced circular members in axial alignment with each other, a bearing at the axis of each circular member, a tubular shaft on which said open frame is rotatably mounted, a trackway extending through the axis of said tubular shaft, connecting means between the trackway and shaft permitting axial movement of the shaft on the trackway, article holding means arranged at intervals about the periphery of each circular member, and frame position regulating means connected to said bearings and extending radially beyond the supported article.
